PIKE AND HOOK ATTACHMENT FOR PADDLES

John W. Johnson, St. Maries, Idaho

Filed Mar. 24, 1958, Ser. No. 723,389

3 Claims. (Cl. 114—230)

The present invention relates to a pike and hook attachment for paddles.

Those who operate launches, runabouts, and other small watercraft have found that a paddle is an essential piece of boating equipment. Many have also found a pike pole to be of considerable use for fending off floating objects, pulling the craft into docks, etc. There is, however, very little, if any, storage space in small boats, and those who keep pike poles in addition to their paddles frequently find difficulty in storing them where they do not interfere with proper use of the boat. Because of the storage problem, many boat operators do not keep pike poles at all, but attempt to use their paddles as substitutes. Paddles, having smooth rounded edges, are ill suited for such purposes. Damage and/or injury often result from their use.

It is the purpose of my invention to provide a simple pike and hook attachment for a paddle which will convert the paddle into a useful and efficient pike pole and which will not hinder, defeat, or diminish the use of the paddle as such.

My invention does away with the necessity of keeping a cumbersome pike pole in the boat in addition to the necessary paddle, and also prevents the frequent damage and/or injury that result from attempts to use paddles as pike poles. My invention is also simple and economical, both to construct and to install on a paddle.

The exact nature and advantages of my invention will appear more clearly from the following description and the accompanying drawings, wherein preferred forms of the invention are shown. It should be understood, however, that the drawings and description are illustrative only and are not intended to limit the invention except insofar as it is limited by the appended claims.

In the drawings:

Figure 1 is a view illustrating a paddle equipped with my invention being used to pull a boat into a dock;

Figure 2 is a view showing a paddle equipped with my invention used to fend off a floating object;

Figure 3 is an enlarged fragmentary elevational view of a paddle having my improved pike and hook attachment mounted thereon;

Figure 4 is a sectional view taken on the line 4—4 of Figure 3;

Figure 5 is a fragmentary elevational view similar to Figure 3, but showing a modified form of the invention;

Figure 6 is a fragmentary elevational view similar to Figure 3, but showing another modified form of the invention; and

Figure 7 is a sectional view taken on the line 7—7 of Figure 6.

Referring now in detail to the drawings, I have shown in Figures 1 and 2 a paddle 10 of standard design upon which my invention is mounted. The paddle 10 comprises a shaft or handle 11 having a blade 12 at one end thereof. My unique pike and hook attachment, generally indicated at 13, is mounted at the free end of the blade 12. The attachment 13 provides on the paddle 10 out-

2

wardly projecting pike point means 14 and a transversely extending hook 15, thus adapting the paddle 10 for use as an effective pike pole.

As shown in Figures 3 and 4, the attachment 13 comprises a plate 16, which carries the point 14 and hook 15, that is affixed to the end of the paddle blade 12 by brackets 17 and 18. The plate 16 is shaped as a segment of a circle and has a straight chord edge 19 and a curved arc edge 20. The chord edge 19 is butted against the end 10 of the blade 12, the tip of the blade 12 being sawed off along a straight line as shown at 21 to receive the plate 16. The plate 16 is wider than the paddle blade 12, as clearly shown in the drawings, and is positioned so that it extends outwardly at one side thereof. This outwardly extending portion forms the hook 15. The point 14 is formed on the arc edge 19 of the plate 16, and is offset from the center of the plate 16 so that it is positioned on the longitudinal center line of the blade 12.

The brackets 17 and 18 which serve to mount the plate 16 on the blade 11 are substantially thin as shown in Figure 4, and are rigidly secured to the plate 16 at each side by spot welds 22. It will be understood, of course, that other means of affixing the brackets 17 and 18 to the plate 16 may be used, as for example, rivets, etc., without departing from the invention. The brackets 17 and 18 are secured to the paddle blade 12 by rivets 23, or by any other suitable means such as screws or the like, and hold the plate 16 rigidly in place at the end of blade 12.

As illustrated in the drawings, the attachment 13 lies wholly within the plane of the paddle blade 12, and thus does not interfere with use of the paddle as such when it is needed. The device is small, and may be constructed of light material so that it does not materially affect the weight or balance of the paddle. Yet, as shown in Figures 3 and 2, it converts the paddle 10 into an effective pike pole that may be used to grasp or fend off objects. The transversely extending sharp protruding edge 15 forms an efficient hook that may be used as shown in Figure 1 to draw a boat A into a dock B or to draw other objects 40 to the boat. The point 14 provides means for gripping objects which are to be fended off, such as the log C shown in Figure 2.

In Figure 5, I have shown a slightly modified form of the invention wherein the point means on the arc edge 20' of the plate 16' are formed as a plurality of small teeth or serrations 24. With this construction, the user is assured of obtaining a sufficient grip on the object he is contacting even though he may strike off center.

In Figure 5, I have also shown the brackets 17' and 18' shaped somewhat differently than in the main form of the invention. It will be understood, of course, that the shaping of the brackets has no particular significance.

In Figures 6 and 7, I have shown a further modification of the invention wherein the attachment 13" is cast as one piece, and shaped to be received on the paddle 55 blade 12 without the necessity of sawing the tip off the blade. The attachment 13" is formed so that it does not cover the whole of the blade end, but terminates immediately to the left of the point 14". The hook 15" is the same as in the other forms of the invention, and as 60 in the other forms, the attachment is secured on the blade 12 by rivets 23.

While I have shown but three forms of the invention in the drawings, I do not intend to limit my invention to the precise construction illustrated. It is obvious that the several construction features illustrated may be combined in other ways. For example, the attaching brackets of the devices shown in Figures 3 and 5, may be cast integral with the plates 16 and 16' as shown in Figure 6. Also the devices shown in Figures 2, 3 and 6 may be provided 65 with the serrated point means 24 shown in Figure 5. In each case, the pike and hook attachment provides point

means and hook means at the tip of the paddle blade, converting the paddle into an efficient pike pole without affecting its utility as a paddle.

It is believed that the nature and advantages of my invention appear clearly from the foregoing.

Having thus described my invention, I claim:

1. A pike and hook attachment for the flat blade of a paddle comprising a flat plate juxtaposed to the end of the blade and lying in the plane of the blade thereby forming an extension of said paddle blade, said plate being 10 shaped substantially as a segment of a circle and having an edge substantially conforming to the end edge of the blade and a curved arc edge, said edges intersecting at one corner to form a point, said plate being offset laterally from the blade whereby to project said point laterally 15 beyond the side edge of the blade to form a hook, said plate having point means on the arc edge thereof project-

ing away from the blade, and flat bracket means on the plate supporting the plate on the blade.

2. The invention defined in claim 1 wherein the point means comprises a V-shaped projection extending axially of the blade from the arc edge of the plate.

3. The invention defined in claim 1 wherein the point means comprises a plurality of outward projecting teeth on the arc edge of the plate.
